COMBINED DISPLAY AND CHARGING UNIT FOR BATTERY OPERATED TOOTHBRUSHES

Theodore Friedman, Glen Ellyn, Ill., assignor to Sunbeam
Corporation, Chicago, Ill., a corporation of Illinois

Filed June 30, 1964, Ser. No. 80,651

Term of patent 14 years

(Cl. D4—3)

FIG. 1 is a front perspective view of a combined display and charging unit for battery operated toothbrushes embodying my new design;

FIG. 2 is an enlarged side elevation view thereof when viewed from the left-hand side of FIG. 1;

FIG. 3 is a top plan view thereof; and

FIG. 4 is a rear elevation view thereof.

The dominant features of my design reside in the portions shown in full lines.

The power handle and toothbrushes, shown in broken lines in FIG. 1, are included for illustrative purposes only.

I claim:

The ornamental design for a combined display and charging unit for battery operated toothbrushes, as shown and described.
